ANTENNA SYSTEM

George H. Brown, Haddonfield, N. J., assignor to
 Radio Corporation of America, a corporation of
 Delaware

Application March 24, 1937, Serial No. 132,679

5 Claims. (Cl. 250—33)

My invention relates to antennas. More particularly, my invention has for its purpose to provide means for energizing co-linear juxtaposed antennas. In one form, by invention 5 is applied to a plurality of vertical half-wave antennas placed end to end in the same straight line whereby the antennas are fed at their junctions. In a modification, I arrange a pair of end to end vertical antennas so that they are energized at their junction and at the base of one 10 of the antennas.

I am aware that a pair of half-wave antennas, placed end to end in the same straight line and energized at their base, have a current distribution 15 in which the current in one of the antennas is out of phase with the current in the other antenna. The so-called "Franklin" antenna overcomes this difficulty of out of phase currents by employing a current phase reversing section 20 between the two antennas. In such Franklin antennas, the currents in the lower radiator are in phase with the currents in the upper radiator. Such an arrangement, while desirable in theory, has two practical drawbacks: First, the proper 25 operation of a phase reversing section is neither easily obtained nor constant in practice; and second, it is not always desirable to have the currents equal in both radiators.

One of the objects of my invention is to provide 30 means for energizing a pair of co-linear end to end antennas at a point between said ends.

Another object is to provide means for impressing radio frequency currents between the 35 adjacent ends and at the base of co-linear juxtaposed vertical antennas.

A further object is to provide means for altering the ratio of radio frequency currents impressed in the upper and lower sections of co-linear end to end vertical dipole antennas.

A still further object is to vary the angle of 40 radiation of a pair of co-linear end to end dipole radiators.

I propose to achieve these objects and overcome the aforementioned difficulties by means of 45 my invention, which is more fully described by reference to the accompanying drawings.

Figures 1A, 1B and 1C illustrate, respectively, the current distribution in co-linear juxtaposed 50 half-wave length vertical antennas in which currents are fed at the junction of the two antennas, between one of the antennas and ground, and at both the junction and the ground connection;

Figures 2A and 2B are graphs showing the 55 angle of radiation and the electrical field about

an antenna system of the character illustrated in Figure 1C; and

Figure 3 illustrates one practical embodiment of my invention.

In Fig. 1A, vertical, co-linear, end to end half-wave antennas 1 and 3 are energized by a high frequency generator E, at the junction of antennas 1 and 3. Assuming that the currents in the antennas are equal, the current distribution in the two antennas 1, 3 is represented by the 10 dash lines 5 and 7.

Fig. 1B illustrates a pair of co-linear, end to end half-wave antennas 9 and 11, which are energized between earth and the base of antenna 11, by generator E'. Assuming that the antennas 15 9, 11 are each a half-wave length long, and have alternating currents flowing therein, the current distribution is represented by the dash lines 13 and 15. It will be observed that one current 13 is of opposite phase with respect to the other, 15. 20

In Fig. 1C I have illustrated a pair of half-wave antennas 17 and 19, which are energized at two points. One of these points represents the generator E, which is connected at the junction of the antennas 17, 19. The other generator E' 25 is connected between the lower end of antenna 19 and earth. It will be seen that the present system represents a combination of the systems illustrated in Figs. 1A and 1B. The current distribution in the present system (Fig. 1C) is represented by dash lines 21 and 23. These lines represent the algebraic sum of the currents resulting from currents impressed by the generators at the junction of the antennas and at the base of one of the antennas. 35

It will be apparent that as the relative value of the in phase and out of phase currents in the two antennas is changed, the current distribution will be altered. I have found that the effective service area of the antenna and generator system of 40 my invention may be varied by varying the proportion of the currents in the two radiators. In general, high angle radiation is considered undesirable because such radiation increases fading in the ordinary service area. In certain installations, however, high angle radiation may be desired. Such radiation may be controlled, as will 45 hereinafter be described.

In Fig. 2A, I have represented the angle of radiation by Φ , and the electric field by F. In 50 Fig. 2B, by a series of graphs, I represent the relative characteristics which may be obtained by varying the ratio of current in the upper antenna with respect to the current in the lower antenna. If the current in the lower antenna is 55

considered unity, and the current in the upper antenna is represented by M , the curves of Fig. 2B represent ratios from $M = -25$ to $M = \infty$. For the optimum suppression of fading within the ordinary service area, the ratio

$$\frac{M}{1}$$

should equal a value between .5 and .75.

In the practical application of my invention, it will be realized that it would be very difficult to energize an antenna which comprises relatively tall radiators, at their mid-points, because of obvious constructional difficulties. While an ordinary transmission line might be employed, its presence will deleteriously affect the lower radiator. However, I propose to use the lower antenna as a combination of radiator and transmission line, whereby the generator or transmitter may be placed at the base of the antenna, as shown in Fig. 3.

A transmitter 25 is connected to a transformer 27 which includes a primary 29 and a center tapped secondary 31. The center tap is connected to the secondary 33 of a transformer 35, whose primary 36 is coupled through the phase control and tuning control network 37, to the transmitter 25.

The center tapped secondary 31 has its outer terminals connected to a transmission line 39 which comprises a pair of conductors 41 and 43, a coaxial cable or the like. These conductors terminate in the primary winding of a transformer 45. The primary winding has a center tapped terminal which is connected to the secondary coil 47. The secondary coil in turn is connected to a half-wave radiator 49, which may be either a single conductor or, for purposes of symmetry, a pair of conductors 51 and 53. The entire antenna system is preferably supported by a non-conductive mast 55.

Having described the circuits, I shall now briefly describe the operation of the system. Currents from the transmitter 25 are induced in the half-wave transmission line 39, through the transformer 27. The currents induced in the secondary 31 flow in opposite directions through the conductors 41, 43. These currents induce currents in the secondary 47 of the transformer 45. The currents thus induced in the secondary 47 flow in the conductors 51, 53 of the upper antenna and in the conductors 41, 43 of the lower antenna, just as the currents represented by the dash lines 5, 7 are distributed in the antennas 1, 3 of Fig. 1A.

In order that additional currents may be radiated from the lower half-wave antenna section in the same phase with the currents induced by the transformer 45, the phase control and tuning network 37 is adjusted so that the additional currents, flowing through this network, and induced in the secondary 33 of the transformer 35, are in the proper phase. Since these additional currents in the two conductors 41 and 43 are in the same phase, due to the center tap connection on the secondary 31, these currents will be radiated from the transmission line 39.

It will be apparent that the coupling between the primary and secondary in each of the transformers 27, 35 and 45 may be adjusted to control the ratio of the currents in the upper and lower radiators to thereby obtain the desired angle of

radiation and resulting effective service area about the antenna system.

From the foregoing description, it will be seen that I have described a pair of vertically disposed, co-linear juxtaposed, half-wave antennas which may be energized at their junction and also between the lower antenna and earth. The ratios of the currents may be regulated to thereby obtain the desired characteristic field about the antenna.

It should be understood that my invention may be applied to vertically arranged systems, or to a horizontal arrangement, or any other angle that may be desired. It should also be understood that while I have shown the invention applied to two radiators of half-wave length each, other numbers of radiators of differing effective lengths may be used.

I claim as my invention:

1. An antenna including in combination a first radiator, a second radiator comprising a two conductor transmission line, means including out of phase currents in the conductors of said second radiator for impressing in phase currents of the same frequency on said first and second radiators, and means for varying the ratio of the currents impressed on said radiators to thereby vary the angle of radiation from said radiators.

2. An antenna system including a co-linear end to end pair of antenna sections; one of said sections including a transmission line, non-radiating for out of phase currents, for impressing radio frequency currents on the other of said sections; other means for impressing in phase radio frequency currents of the same frequency on the section including said transmission line whereby said second mentioned radio frequency currents may be radiated from said transmission line, and means for varying the ratio of the radio frequency currents in said sections to thereby determine the angle of radiation from said sections.

3. In an antenna system, a half-wave antenna; a second half-wave antenna being disposed co-linearly and end to end with respect to said first antenna; said second antenna including a two conductor transmission line carrying out of phase currents for energizing said first antenna, means for impressing said out of phase currents on said first antenna in phase; means for impressing said out of phase currents on said second antenna, and including means whereby said currents in said second antenna are in phase in the conductors of said transmission line and in phase with and of the same frequency as the currents impressed on said first antenna.

4. An antenna system including in combination a pair of half-wave dipole antennas, the first of said pair including a two conductor transmission line, means for impressing out of phase currents in the conductors on said transmission line, means for impressing said out of phase currents on the second of said antennas, and means for impressing in phase currents in the conductors of said transmission line, said currents being in phase with and of the same frequency as the currents in said second antenna.

5. In a device of the character of claim 4, means for varying the ratio of the in-phase currents in said antennas.
